MINIATURIZED FLUID MECHANICS LABORATORY CENTER

Donald A. Gilbrech, 417 Government Ave.,
Fayetteville, Ark. 72701

Filed July 28, 1966, Ser. No. 3,247

Term of patent 14 years

(Cl. D16—2)

FIG. 1

FIG. 2

FIG. 3

FIGURE 1 is a side elevational view of a miniaturized fluid mechanics laboratory center. The right side is the mirror image of the left side.

FIGURE 2 is a front elevational view of the portable laboratory center.

FIGURE 3 is an isometric view of the portable laboratory center.

The back, thereof, is a conventional plane panel.

I claim:

The ornamental design for a miniaturized fluid mechanics laboratory center, substantially as shown and described.
